UNITED STATES PATENT OFFICE.

ALBERT W. WINSHIP, OF UTICA, NEW YORK.

WARDROBE TRUNK.

Application filed February 7, 1921. Serial No. 443,258.

To all whom it may concern:

Be it known that I, ALBERT W. WINSHIP, a citizen of the United States, and a resident of Utica, in the county of Oneida and State 5 of New York, have invented certain new and useful Improvements in Wardrobe Trunks; and I do hereby declare that the following is a full, clear, and exact description thereof, which will enable others skilled in the art 10 to which it appertains to make and use the same, reference being had to the accompanying drawings, and to the reference numerals marked thereon, which form part of this specification.

15 My present invention relates to wardrobe trunks meaning thereby as is usual in the trunk business today trunks having a wardrobe section where clothes may be hung up usually upon a rack and another section 20 which is equipped with drawers or other suitable receptacles.

The purpose of my present invention is to provide an improved trunk of the character described, one which is novel in construction, convenient in use and strong enough to 25 resist the hard usage to which trunks are subjected.

It has been common heretofore in centrally opening wardrobe trunks to have the 30 open side of the wardrobe section towards the inner side of the chiffonier or the drawer section, that is towards the side of the chiffonier section which faces the wardrobe section, but in such trunks the drawers of 35 the chiffonier section have drawn out through the inner side of the chiffonier section, that is the open side of the chiffonier section has been the side facing the inner or open side of the wardrobe section.

40 The disadvantage of that construction is that the two sections or halves of the trunk have to be swung out on their hinges past a right angle and in practice substantially in a straight line in order to allow the drawers to be drawn out. One purpose of my 45 present invention is to overcome the disadvantages of that form of a centrally opening wardrobe trunk which I do by having the forward side of the chiffonier section the 50 open side and have the drawers slide out through said open side. It is the purpose therefore of this invention to combine properly in a centrally opening wardrobe trunk a wardrobe section opening on its inner side 55 and a chiffonier section opening on its front side.

It is a still further object of this invention to provide a centrally opening wardrobe trunk of the character described having a closure for covering the front of the drawers which closure furthermore forms a means for detachably but strongly connecting the forward inner edge of the wardrobe section to the outer forward edge or corner of the chiffonier section. 60

Another object is to provide in a centrally opening wardrobe trunk the feature of drawers sliding in the line of their length instead of crosswise of their long dimension. 65

A further purpose is to provide a centrally opening wardrobe trunk wherein the chiffonier section has at its inner side a strong partition either entirely solid or heavily panelled forming a partition and brace 70 extending from the forward inner edge of the chiffonier section to the rear inner edge of the chiffonier section; and further to provide in combination therewith a light swinging door forming not only a closure for the 75 open front of the chiffonier section, but also means for securely but detachably connecting and interbracing the forward inner edge of the wardrobe section with the outer forward edge or corner of the chiffonier section. 80

Further purposes and objects of my invention are to provide constructions, combinations and arrangements of parts in a wardrobe trunk particularly adapted to accomplish the foregoing purposes. 85

Fig. 1 is an isometric projection of a trunk embodying my invention with its two sections opened but with the two sections of the trunk still together. 95

Fig. 2 is an isometric projection of said trunk with its two sections moved apart on their hinges to give full access to the wardrobe section.

Fig. 3 is a vertical sectional view through 100 the top of the chiffonier section and the top of the wardrobe section showing a modified form of top closure for the wardrobe section.

Fig. 4 is a detail horizontal sectional view 105 on an enlarged scale of the meeting forward edges of the two sections of the trunk.

Referring to the drawings in a particular description, it will be seen that the trunk consists of a wardrobe section 8 and a chiffonier section 9 hinged together along their 110 adjacent inner rear vertical edges by a suit-

able number of hinges 10, a closure 11 for the open top of the wardrobe section and a closure 12 for the open front of the chiffonier section.

5 The wardrobe section 8 has a bottom 13, a front side 14, a rear side 15 and an outer side 16 all rigidly and permanently fastened together leaving said wardrobe section open at its top and also open at its inner side 10 meaning the side towards the chiffonier section and so the side of the wardrobe section which is inside when the trunk is closed.

The chiffonier section 9 is composed of a bottom 17, a rear side 18, an outer side 19, 15 a top 20 and an inner side 21 either solid or panelled all rigidly and permanently fastened together and leaving said chiffonier section with its forward side open.

I have shown the chiffonier section 9 as 20 provided with a plurality of drawers 22 mounted in the section between front drawer guides 23 and corresponding internal drawer guides 23^a as this equipment is the preferred one and will be usual in the full embodiment 25 of my invention. It will be understood, however, that in the broadest form of my invention the particular arrangement or character of these containers in the chiffonier section is not the essential feature, but rather that of 30 having said wardrobe section open at its forward side with the containers removable therefrom lengthwise of the section and with the opening closed by a closure which is a means of detachably connecting the forward 35 inner edge of the wardrobe section to the outer forward edge or corner of the chiffonier section. Where as is the usual construction and is also the preferred construction in my 40 complete combination, the drawers 22 are used it will be seen that they slide lengthwise of the drawers which produce the free sliding and non-cramping drawer such as found in a desk in contradistinction to a drawer sliding on its short sides or at right angles 45 to its length as is commonly found in a chiffonier or bureau and as has heretofore been used in a centrally opening wardrobe trunk. This lengthwise sliding of the drawers produces a free sliding and non-cramping 50 drawer not only as against sidewise cramping but as against vertical cramping so that the drawer can be drawn out a long distance without dropping down or cramping so much as to prevent readily shoving the drawer 55 back into place.

The inner side 21 of the wardrobe section is constructed either as a solid partition or as a deeply panelled member so that the inner side of the chiffonier section forms a 60 strong inner side for the chiffonier section operating to tie together very strongly the inner edges of the top 20, bottom 17 and rear side 18 and forming a very strong bracing member preventing any annular or diagonal 65 distortion of the chiffonier section at its in-

ner side or edge. This strengthening and bracing action, however, is further directly lent to the open inner side of the wardrobe section in that the rear side 15 has its inner edge attached directly to the inner edge of 70 the rear side 18 of the chiffonier section by hinges 10 and in that the forward side 14 of the wardrobe section when the trunk is closed has its inner edge closely aligned with the forward edge of said panelled inner side 75 21 of the chiffonier section by means which will be hereinafter more particularly described and also in that the inner edge of the bottom 13 of the wardrobe section will be closely aligned with the bottom edge of 80 the said panel section of the chiffonier section when the two sections are closed whereby any bulging downward of the inner edge of the bottom 13 will be prevented through 85 the valance strip 24 on the inner edge of the bottom 17 overlapping the adjacent inner edge of the bottom 13.

The closure 12 forms not only the closure proper for the open front of the chiffonier section, but at the same time forms very 90 strong means for detachably connecting the inner edge of the wardrobe section front side 14 with the forward outer edge or corner of the chiffonier section and so binding and bracing the two sections of the trunk well 95 together when the trunk is closed. In my preferred form and as shown in the drawings said closure 12 has one edge attached to the inner edge of the front side 14 by a plurality of hinges 25 while the other side 100 of said closure is adapted to closely fit the forward edge of the outer side 19 of the chiffonier by means of valance strip 26 on said closure overlapping the outside of said forward edge of outer side 19 and by said 105 closure having its outer edge detachably secured to the forward edge or corner of the outer side 19 of the chiffonier section by means of a plurality of spring catches 27 and a lock 28 of any desired form. 110

Preferably the valance strip 26 will be extended as at 26^a along the top edge of the closure 12 so as to overlap and closely fit the outside of the forward edge of the top 20 of the chiffonier section. 115

In order to admit of the closure 12 being opened without striking or swinging upon the floor, I prefer to have said closure a little shorter than the height of the trunk and not extend quite to the bottom of the chiffonier 120 section. Accordingly the chiffonier section has a small front piece 29 extending from the bottom up a few inches to the line where the drawers 22 begin. The space thus provided in the bottom of the chiffonier section below 125 the lowermost drawer may be used for storage and is accessible upon taking out the lowermost drawer.

Suitable means are provided apart from the closure 12 for detachably fastening the 130

inner edge of the front 14 of the wardrobe section to the inner forward corner of the wardrobe section prior to the shutting of the closure 12 and so operating to hold the two 5 sections of the trunk as well together after the closure 12 and also closure 11 have been opened. As means for this direct fastening there is provided a flat spring 30 projecting from the inner surface of the inner edge of 10 the front 14 across the open front of the chiffonier section and adapted to engage a projecting lug 31 suitably located upon the chiffonier section as by being placed upon one of the forward drawer guides 23.

15 While I have shown and particularly described the closure 12 as being hinged to the wardrobe section and detachably fastened at its corner edge to the corner of the chiffonier section, it will be obvious that the reverse of 20 this arrangement is within the scope of my invention and within some of the claims hereinafter set forth.

As shown in Figs. 1 and 2 of the drawings the closure 11 for the open top of the wardrobe section is secured by hinges 32 to the inner edge of the top 20 of the chiffonier section and the outer edge of said closure is detachably fastened to the outer edge of the outer side 16 of the wardrobe section as by 30 spring catches 33 and lock 34. From the free edges of the top 11 there also projects downwardly a valance strip 35 overlapping the outside of the wardrobe section about its upper outer edges. It will be obvious that 35 in this construction this top closure 11 being hinged along the line of the panel or partition 21 of the chiffonier section is well secured at that edge and through its overlapping valance strip and its lock 34 is well

40 secured to the wardrobe section and adds greatly to the strength of the upper end of the top of said wardrobe section when said closure is in place as it always will be during transit or handling of the trunk. It will 45 be noted that with this arrangement of the closure 11, access may be had to the wardrobe section independently of the closure 12 and entirely independent of the outwardly hinging action of the two sections of the 50 trunk. In other words a user of the trunk desiring to get a garment from the wardrobe section can simply unlock and open the top closure 11 and reach down into the wardrobe section for the desired article without 55 having to unlock or open the closure 12 and without having to swing the two halves or sections of the trunk open.

It will be seen that one advantage of my invention is that access can readily be had to 60 the drawers 22 of the chiffonier section or to the compartment below the lower drawer in back of the small side piece 29 by simply unlocking and opening the front closure 12 and without having to open the top closure 65 11 and also without having to swing the

wardrobe section and the chiffonier section apart upon the hinges. A further advantage incident to this front opening of the chiffonier section is that the drawers slide lengthwise and so free and without cramping and still further that through the drawers sliding lengthwise thereof and through the front of the chiffonier section instead of through its side the two sections of the trunk need only be swung to right 70 angles to each other in order to give full and convenient access to both the drawers and the wardrobe section. There follows from this fact the further advantage that this trunk when moved to its normal fully opened 75 position, namely with its sections at right angles to each other, does not occupy as much space as the usual central opening trunk which has to have its two sections swung practically back into a straight line. 80 Furthermore, the fact that this trunk has both of its parts fully accessible when its parts are at said right angles to each other results in the trunk being steadier and practically incapable of being tipped over in that 85 each section acts as an angular anchor for the other section. This is a decided advantage over the central opening trunks which when fully swung open are very liable to tip back or forward in that they have a very 90 narrow base in proportion to the height. At the same time my wardrobe trunk is entirely capable of having its two sections opened up to be in line with each other when desired and is fully usable at that position. 95

100 Fig. 3 is a detail showing a modified form of my trunk in that the top closure 11^a is hinged at its outer edge to the outer edge of the outer side 16 of the wardrobe section and the inner edge of said closure is detachably 105 secured to the inner edge of the top 20 of the chiffonier section. With this form of top closure the inner or free edge of the closure will when the two sections of the trunk are brought together be inside a valance strip 110 36 projecting out from the top 20. Obviously this form of closure cannot be opened without the two halves or sections of the trunk being first opened up. With this form of construction, however, the necessity for 115 an additional lock or spring catches for the top closure is dispensed with in that the said top closure is automatically locked when the wardrobe section and chiffonier section are again swung together.

120 Means are provided for having the forward inner edge of the front side 14 of the wardrobe section and the front inner corner of the chiffonier section closely engage and re-inforce each other when the two sections of the trunk are closed. A convenient and the preferred form for such means are a cleat 41 securely fastened to the inner surface of the side 14 adjacent its edge and a cleat 42 securely fastened to the panel 21 of 130

the chiffonier section a short distance back from its forward edge as shown in Fig. 4. The forward edge of cleat 41, that is the side appearing in Fig. 2 will when the two sections of the trunk are brought together fit against the portion 21^a of the panel 21 forward of cleat 42 and so prevent the side 14 from being drawn past its proper position. At the same time the forward side 42^a of the 10 cleat 42 will be engaged by the surface of the cleat 41 farthest from the side 14 and so prevent the side 14 from being pressed inward past its proper position.

What I claim as new and desire to secure 15 by Letters Patent is:

1. A centrally opening wardrobe trunk consisting of a wardrobe section and a chiffonier section hinged together along their rear adjacent vertical edges, means for detachably securing the front adjacent edges of the two sections independent of the closures therefor, the wardrobe section being open on its inner side whereby opening of the trunk along its center gives access to the 20 wardrobe section, the chiffonier section being open at its front side and having a panel facing the wardrobe section and connecting the inner edges of the top, bottom and rear and front sides of the section and a closure 25 for said front side of the chiffonier hinged to the front inner edge of the wardrobe section and forming means to detachably connect the front inner edge of the wardrobe section and the outer front edge of the 30 chiffonier section.

2. A centrally opening wardrobe trunk consisting of a wardrobe section and a chiffonier section hinged together along their rear adjacent vertical edges, means for detachably securing the front adjacent edges of the two sections independent of the closures therefor, the wardrobe section being open on its inner side whereby opening of the trunk along its center gives access to the 35 wardrobe section, the chiffonier section being open at its front side and provided with drawers sliding out through said open front side, the chiffonier section also having a panel facing the wardrobe section and connecting the inner edges of the top, bottom and rear and front sides of the section and a closure for said front side of the chiffonier forming means to detachably connect the front inner edge of the wardrobe section and the other front edge of the chiffonier section.

3. A centrally opening wardrobe trunk consisting of a wardrobe section and a chiffonier section hinged together along their rear adjacent vertical edges, means for detachably securing the front adjacent edges of the two sections, the wardrobe section being open on its inner side whereby opening of the trunk along its center gives access to the wardrobe section, the chiffonier section being 65 open at its front side and provided with

drawers sliding out through said open front side, the chiffonier section also having a panel facing the wardrobe section and connecting the inner edges of the top, bottom and rear and front sides of the section and a closure for said front side of the chiffonier hinged to the front inner edge of the wardrobe section and detachably secured to the forward outer edge of the chiffonier section.

4. A centrally opening wardrobe trunk 75 consisting of a wardrobe section and a chiffonier section hinged together along their rear adjacent vertical edges, means for detachably securing the front adjacent edges of the two sections, the wardrobe section being open on its inner side whereby opening of the trunk along its center gives access to the wardrobe section, the wardrobe section being open at its top, a closure for the top opening of the wardrobe section, the chiffonier section being open at its front side and provided with drawers sliding out through said open front side, the chiffonier section also having a panel facing the wardrobe section and connecting the inner edges of the top, bottom and rear and front sides of the section and a closure for said front side of the chiffonier hinged to the front inner edge of the wardrobe section and forming means to detachably connect the front inner edge of the wardrobe section and the outer front edge of the chiffonier section.

5. A centrally opening wardrobe trunk 80 consisting of a wardrobe section and a chiffonier section hinged together along their rear adjacent vertical edges, means for detachably securing the front adjacent edges of the two sections, the wardrobe section being open on its inner side whereby opening of the trunk along its center gives access to the wardrobe section, the wardrobe section being open at its top, a closure for said top opening of the wardrobe section hinged to the chiffonier section along its top inner edge 85 and overlapping the top edges of the wardrobe section, the chiffonier section being open at its front side and provided with drawers sliding out through said open front side, the chiffonier section also having a panel facing the wardrobe section and connecting the inner edges of the top, bottom and rear and front sides of the section and a closure for said front side of the chiffonier hinged to the front inner edge of the wardrobe section and forming means to detachably connect the front inner edge of the wardrobe section and the outer front edge of the chiffonier section.

6. A centrally opening wardrobe trunk 125 consisting of a wardrobe section and a chiffonier section hinged together along their rear adjacent vertical edges, means for detachably securing the front adjacent edges of the two sections, the wardrobe section be-

ing open on its inner side whereby opening of the trunk along its center gives access to the wardrobe section, the wardrobe section being open at its top, a closure for said top 5 opening of the wardrobe section hinged to the chiffonier section along its top inner edge and overlapping the top edges of the wardrobe section, the chiffonier section being open at its front side and provided 10 with drawers sliding out through said open front side, the chiffonier section also having a panel facing the wardrobe section and connecting the inner edges of the top, bottom and rear and front sides of the section and a 15 closure for said front side of the chiffonier hinged to the front inner edge of the wardrobe section and detachably secured to the forward outer edge of the chiffonier section.

7. A centrally opening wardrobe trunk 20 consisting of a wardrobe section and a chif-

fonier section hinged together along their rear adjacent vertical edges, the wardrobe section being open at its inner side whereby opening of the trunk along its center gives access to the wardrobe section, the chiffonier 25 section having a complete solid bottom but being open at its front side thereabove and having a panel facing the wardrobe section and connecting the inner edges of the top, bottom and rear and front sides of the section and a 30 closure for said open part of the front side of the chiffonier hinged to the front inner edge of the wardrobe section and forming means to detachably connect the 35 said front inner edge of the wardrobe section and the outer front edge of the chiffonier section.

In witness whereof I have affixed my signature, this 31 day of January 1921.

ALBERT W. WINSHIP,
